MANUFACTURE OF SOAP

Leopold Sender, Baltimore, Md., assignor to The Sharples Corporation, Philadelphia, Pa., a corporation of Delaware

No Drawing. Application December 9, 1941,
Serial No. 422,231

9 Claims. (Cl. 260—412.5)

The present invention pertains to the manufacture of soap, and is concerned with the problem of obtaining an improved yield of soap or material which can be saponified by further treatment. More specifically, a process is provided by which soap nigres may be subjected to purification for removal of material including dirt and other undesired impurities together with a small part of the soap content of the nigre, from the remainder of the nigre, and the soap or soap-forming acid content of the material removed from the nigre thereafter recovered from the impurities.

Processes for removing impurities from soap nigres have been proposed heretofore, and I do not claim any particular process for effecting such removal as a part of the present invention. One method of effecting such purification consists in simple centrifugation, preferably by a centrifugal containing peripheral discharge outlets controlled by valves through which the impurities are intermittently discharged. In the practice of such a method, the degree of purification attained can be improved by first diluting the nigre with water before subjecting it to centrifugal purification. Another method of purifying a nigre is described and claimed in the co-pending application of Leopold Sender and James H. Wilson, Serial No. 389,888, filed April 23, 1941, for Manufacture of soap. In accordance with this method, the nigre is first treated with a source of acid, which may be an organic or inorganic acid or ester (e.g., a soap-forming ester), in order to reduce the free alkali content of the nigre and convert it to a condition in which the impurities may be more effectively removed upon subsequent centrifugation. The process covered in this application constitutes the best method known to me for effecting removal of impurities, and constitutes the preferred operation by which impurities are removed from the nigre in the practice of the present invention.

In the conventional manufacture of soap, it is customary to utilize the soap values contained in the nigre by mixing the nigre with fat and a saponifying reagent in the formation of a further quantity of soap. The nigre is subjected to the saponification, salting and separating steps along with these fresh quantities of soap-forming constituents, in order that the soap contained in the nigre may become a part of the soap formed in this subsequent soap making operation. In utilizing the soap contained in the nigre in this manner, there are certain economic limitations. In introducing the nigre along with other ma-

terials in the subsequent soap making operation, impurities of the nigre are introduced into the mass from which the subsequent soap is made, and these impurities must, of course, be removed from this subsequently made soap in the fitting step performed on the saponified mass, if this subsequently made soap is to be of a quality comparable to that made in the operation from which the first nigre was obtained. It is customary to 5 re-use the nigre formed in soap making operations as many times as this can be done consistently with production of a soap of satisfactory quality, but a point is inevitably reached in recycling successive batches of nigre at which the 10 nigre contains such a large proportion of impurities that it can no longer be recycled consistently with manufacture of satisfactory soap.

By purifying the nigre by one of the types of 15 operation discussed above before recycling to a subsequent soap making operation, a substantial proportion of the impurities of the nigre is removed, with the result that operations of recycling the nigre may be continued in a longer series of operations than could be done if such 20 purification were not accomplished. The purification of the nigre thus effects an important economy by making it possible to repeat the recycling operation through a longer sequence of operations than could otherwise be feasibly accomplished.

While purification of the nigre before recycling is 25 advantageous for the reasons discussed above, such purification is attended by the draw-back that a certain amount of soap is inevitably lost 30 in connection with the performance of the purification step. In case of separation of the impurities centrifugally, for example, the impurities obtained by the centrifugal operation must of necessity contain a certain amount of soap. In 35 any separating operation, best results as to purification of one of the products of the separation can be attained by permitting the other product to be contaminated with a certain amount of the product which is desired in a maximum state 40 of purity. Thus, in a centrifugal separating operation in which impurities are to be separated from nigre, best results as to separation of the impurities from the nigre can be attained by separating from the main body of the nigre, together with the impurities, a part of the soap 45 values of the nigre. Any attempt to separate these impurities without removing a part of the soap values of the nigre along with the impurities results in impairment of efficiency of separation 50 of the impurities, with the result that realization

of the benefit of efficient removal of the impurities is not attained, and that the number of feasible repetitions of the step of recycling the nigre is correspondingly limited, a result which constitutes partial defeat of the main object of the purification. The operator is thus confronted with the dilemma that, if he effects the best possible purification of the nigre, substantial quantities of soap values are lost, but that, if he attempts to minimize loss of the soap values in the nigre, the purification operation is relatively inefficient, with the result that attainment of the principal object of the purification step becomes impracticable. The attainment of the objects of maximum efficiency of purification with minimum loss of soap values with the impurities thus apparently constitutes an attempt to reconcile essentially irreconcilable factors.

A feature of the present invention consists in the fact that it includes a sequence of steps in removal of impurities from the nigre and recovery of soap values by which maximum efficiency is attained in the purification step, with attendant removal of a substantial part of the soap from the nigre in this step, and the soap values are subsequently recovered from the fraction containing the impurities for reuse in the soap making process, or for other appropriate use to which these soap values or acids derived therefrom may be put.

The first step in the practice of the invention consists in treatment of the soap nigre to remove the dirt and other impurities from the nigre. Such treatment may involve any of the operations discussed above for removing these impurities, or any other treatment by which impurities are removed from the nigre with a certain amount of the soap of the nigre. Regardless of the exact method of purification performed, an attempt is made to conduct this step with maximum efficiency of purification of the nigre, and in order to accomplish this object, the impurities removed from the nigre contain a substantial proportion of soap. By performing the first step of the process in this manner, the main body of the nigre is purified to a degree which will permit it to be mixed with further quantities of soap-forming materials in the manufacture of a further quantity of soap with a minimum of contamination of the further quantity of soap by impurities retained in the nigre from the previous soap making operation.

The performance of the purification step in the manner discussed above obviously entails substantial loss of soap values from the nigre treated. In the practice of the present invention, this loss is compensated by recovery of these values from the impurities with which they are removed from the main body of the nigre in the initial purification step. Thus, in case of separation of dirt from soap nigre in a centrifugal separator of the valve bowl type, impurities are discharged peripherally through the valve-controlled outlets together with a part of the soap of the nigre, with the result that the nigre is satisfactorily purified for reuse, and the peripherally discharged fraction is then subjected to the subsequent steps of the process for recovery of soap contained therein. The removal of the soap values from the impurities with which they are separated from the main body of the nigre may be accomplished by dilution of these impurities with water to dilute the soap, and subsequent separation of the impurities from the resultant soap solution. The diluted soap solution so ob-

tained may be used in the manufacture of a further quantity of soap, or in any other manner by which the soap values which it contains may be utilized.

5 Another method of effecting separation of the soap values from the impurities consists in adding water to the impurities containing the soap values and thereafter salting the soap out of solution in the water by addition of a salt or alkali. This operation liberates the dirt, which is next removed from the mixture of soap and water by appropriate means, such as centrifugation.

As a still further alternative in the practice of the invention, the impurities removed from the nigre and containing the soap may be mixed with a mineral acid capable of sprung the soap to form fatty acids. This sprung operation will liberate the impurities, with the result that these impurities may be separated from the other constituents of the mixture by appropriate means, such as centrifugation, for example, by treating the resulting mixture in a centrifugal separator of the so-called clarifier type in order to separate the impurities from the mixture of sprung acids and aqueous acid liquor, and then separating the sprung fatty acids and aqueous acid liquor by centrifugation or gravity. Alternatively, the separation may be accomplished in a centrifugal of the so-called separator type in which the impurities may be separated peripherally from the centrifugal at the same time that the sprung acids are separated from the aqueous acid liquor.

From the above discussion, it will be seen that a separation of the soap values from the impurities may be attained by treatment with water, salts, alkalies or acids to liberate the impurities and permit them to be separated from the soap by appropriate means, such as centrifugation. As a matter of fact, such separation is facilitated by the addition to the impurities of any liquid diluent, and a feature of the invention consists in the addition of a liquid diluent, followed by centrifugation. While the invention has been discussed above in connection with an operation involving separation of impurities along with soap values from the nigre after the nigre has been separated from the main portion of the initially saponified mass, it is possible to combine the steps of separation of the nigre from the bulk of the saponified mass and the separation of impurities, together with part of the soap values, from the nigre. Thus, by employing a centrifugal separator of the valve bowl type in separation of neat soap from nigre, this separation may be accomplished at the same time that impurities containing soap values are discharged centrifugally from the nigre, which forms an outer stratum in the centrifugal rotor. The present invention therefore includes separation of impurities together with soap values from the nigre, followed by separation of soap values contained in impurities from those impurities, regardless of whether initial separation of the impurities from the nigre is accomplished subsequent to separation of the nigre from neat soap or simultaneously therewith.

Various modifications are possible within the scope of the invention, and I do not therefore wish to be limited except by the scope of the following claims.

I claim:

1. In the treatment of soap nigres, the process comprising separating impurities from a soap nigre together with a portion of the soap of the nigre, thereafter diluting the material separated

from the nigre to liberate impurities from the resulting diluted mixture and separating the impurities from said mixture.

2. In the treatment of soap nigres, the process comprising separating impurities from a soap nigre together with a portion of the soap of the nigre, thereafter diluting the material separated from the nigre to liberate impurities from the resulting diluted mixture and separating the impurities from said mixture by centrifugation.

3. In the treatment of soap nigres, the process comprising separating impurities from a soap nigre together with a portion of the soap of the nigre, thereafter diluting with water the material separated from the nigre to liberate impurities from the resulting diluted mixture and separating the impurities from said mixture.

4. In the treatment of soap nigres, the process comprising separating impurities from a soap nigre together with a portion of the soap of the nigre, thereafter diluting with water and an electrolyte the material separated from the nigre to liberate impurities from the resulting diluted mixture and separating the impurities from said mixture.

5. In the treatment of soap nigres, the process comprising separating impurities from a soap nigre together with a portion of the soap of the nigre, thereafter diluting with water and a salt the material separated from the nigre to liberate impurities from the resulting diluted mixture and separating the impurities from said mixture.

6. In the treatment of soap nigres, the process

comprising separating impurities from a soap nigre together with a portion of the soap of the nigre, thereafter diluting with water and an alkali the material separated from the nigre to liberate impurities from the resulting diluted mixture and separating the impurities from said mixture.

5 7. In the treatment of soap nigres, the process comprising separating impurities from a soap nigre together with a portion of the soap of the nigre, thereafter diluting with water the material separated from the nigre to liberate impurities from the resulting diluted mixture and separating the impurities from said mixture by centrifugation.

10 8. In the treatment of soap nigres, the process comprising separating impurities from a soap nigre together with a portion of the soap of the nigre, thereafter diluting the material separated from the nigre with a mineral acid to spring the soap separated with the impurities and liberate impurities from the resulting mixture, and separating the impurities from said mixture.

15 9. In the treatment of soap nigres, the process comprising separating impurities from a soap nigre together with a portion of the soap of the nigre, thereafter diluting the material separated from the nigre with a mineral acid to spring the soap separated with the impurities and liberate impurities from the resulting mixture, and separating the impurities from said mixture by centrifugation.

LEOPOLD SENDER.
